PROCESS OF AND APPARATUS FOR FIRE-POLISHING GLASS.

No. 899,473.

Specification of Letters Patent. Patented Sept. 22, 1908.

Application filed May 3, 1906. Serial No. 314,994.

To all whom it may concern:

Be it known that I, SOLON OSMOND RICHARDSON, Jr., a citizen of the United States, residing at Toledo, in the county of Lucas and State of Ohio, have invented certain new and useful Improvements in Processes of and Apparatus for Fire-Polishing Glass, of which the following is a specification.

My invention relates to improvements in the art of polishing glass by means of flame, and has for its object the provision of means whereby the interior surface of glass articles may be simply and effectively polished without distorting or in any way affecting the form of the article subjected to such treatment. My invention is especially useful in such treatment of pressed-glass articles. These, and such other objects as may hereafter appear, are attained by my invention, which may be conveniently embodied in, and practiced with, the apparatus shown in the accompanying drawings, in which

Figure 1 shows one form of apparatus. Fig. 2 is a detail. Fig. 3 is another detail; and Fig. 4 shows a modified form of apparatus.

Like letters of reference indicate the same parts in the several figures of the drawings.

Referring by letter to the accompanying drawings, A indicates a brick foundation provided preferably with a supporting shelf B.

C is a fire-box supported on the foundation A and arranged to receive a fuel burner D. Preferably the fuel burner D suplies fuel oil under pressure and communicates with an opening E in the box C, through which sufficient air for combustion may enter around the burner D. The box C is otherwise closed, except for the discharge nozzle F, which extends downwardly toward the shelf B.

It will be noted that to insure more perfect combustion in the fire-box, the nozzle F is preferably arranged at a point remote from the inlet opening E and also extends at right angles to the line of entrance of the fuel jet from the burner D, so that the tendency will be to cause the fuel jet to strike against the sides of the fire-box and be broken up thereby, so as to be intimately intermingled with the oxygen of the air, thus promoting combustion and lessening the tendency to establish a direct jet from the burner D through the discharge nozzle.

A cast-iron plate G may be conveniently

mounted upon the shelf B, and a former H may be rested upon the plate G and below the nozzle F.

In practicing my invention, any desired fuel is projected into the fire-box C through the burner D. Preferably the burner D projects a spray of fuel oil into the fire-box, and a sufficient volume of air also is supplied to the fire-box, either through the opening E or otherwise, with the result that the spray of fuel oil, if oil be used as a fuel, and the oxygen-bearing element, such as air, are thoroughly intermingled and combined in the fire-box C, which thus constitutes a combustion chamber. Consequently, the fire-box being properly proportioned, a body of live flame, at an exceedingly high temperature, resulting from the perfect combustion of the fuel elements, will be projected downwardly through the nozzle F. To utilize this flame in the fire polishing of pressed-glass articles, for example, I remove the glass blank h from the pressing mold as soon as it is sufficiently set to permit of such handling without distortion, and place it in the former H, which will ordinarily, though not necessarily, be materially cooler than the glass blank. I then place the former H under the nozzle F, so that the body of live flame projected from the nozzle F will be forced directly into the interior of the glass blank and will sufficiently soften the interior surface of the blank to obliterate all mold marks and give the desired fire polish. The former will serve, to a greater or less extent, to radiate the resulting heat, so as to lessen the softening effect of the polishing flame upon the body of the blank and, indeed, by suitably constructing the former and providing for free radiation from the exterior surface thereof, in any familiar manner, this result may be attained to such an extent as to avoid such softening of the blank by the polishing flame as would otherwise result in distorting the blank. Aside, however, from such preservation of the form of the blank by the radiation of the heat from the exterior of the former, the former may serve to mechanically inclose and support the exterior of the blank at all points, so as to prevent any change of form in the blank, even though it become heated by the polishing flame to such an extent as to become more or less plastic throughout.

When the blank has been subjected to the polishing flame for a sufficient length of time to obtain the result desired, the former containing the blank is removed from the shelf 5 beneath the nozzle F and, if the blank has been rendered plastic by the polishing flame, it is allowed to remain in the former until it has cooled and become sufficiently set to permit of handling without distortion.

10 In Fig. 4 the fire-box C is mounted upon supports A', providing for a free circulation of air beneath the fire-box and for a very simple and inexpensive construction; and in lieu of the shelf B, I provide a table I, which 15 rotates upon a support J and is adapted to hold a number of blank-containing formers H so as to bring them successively under the nozzle F. With this construction, such a time elapses between the time a former is 20 moved from under the nozzle F until it reaches the extreme outer point in the rotation of the table I that the blank may always be sufficiently cooled and set when it reaches such outer point to permit of the removal of 25 the polished blank and the insertion of an unpolished blank, which will ultimately be carried around and under the nozzle F. These are suggestive and practical embodiments of my improved apparatus for practicing my process.

It will be noted that, among other advantages of my invention, it makes it practical to polish either or both sides of a blank, for, when the blank is removed from the mold, it 35 may, if desired, be mounted upon a former H' which shall support the interior of the blank, as shown in Fig. 3, thus permitting of the polishing of the exterior of the blank, whereupon the blank may be reversed and 40 supported by another suitably shaped former and polished on its interior.

I claim:

1. The process of fire polishing a glass

blank, which comprises forming the blank in a mold, removing the blank from the mold, 45 and then subjecting one surface of the blank to a polishing flame while the surface of the blank opposite the surface against which the polishing flame is directed is supported by means arranged so as to be exposed to the 50 air and out of the polishing flame so as to prevent such opposite surface from becoming plastic.

2. The process of fire-polishing a glass blank, which comprises forming the blank in 55 a mold, removing the blank from the mold and then subjecting one surface of the blank to a polishing flame which is confined to such surface while the surface of the blank opposite the surface against which the polishing 60 flame is directed is supported by means exposed to the air outside the apparatus and arranged so that the flame is not directed against it.

3. In apparatus for fire polishing glass, 65 the combination of a chamber closed on the top and sides, with means for causing the fuel elements to pass horizontally through said chamber, a support for the article to be polished below said chamber, and a nozzle 70 extending downward from the bottom of said chamber toward said support.

4. In apparatus for fire polishing glass, the combination of a support to hold the 75 article to be polished, with a nozzle extending downward toward said support, means for discharging the fuel element in substantially a horizontal direction toward said nozzle, and means for confining the same so as to cause the flames to pass down through 80 said nozzle.
